[57] **CLAIM**

The ornamental design for a computer cable trough for routing computer cables between stacks of computer modules.

DESCRIPTION

FIG. 1 is a perspective view of a computer cable trough for routing computer cables between stacks of computer modules, on a reduced scale, the broken line drawings of stacks of computer modules are for illustrative purposes only and form no part of the claimed design;

FIG. 2 is a top plan view of the computer cable trough for routing computer cables between stacks of computer modules;

FIG. 3 is a bottom plan view of the computer cable trough for routing computer cables between stacks of computer modules;

FIG. 4 is a side elevational view thereof, on an enlarged scale, showing the wider central wall portion, the opposite side being identical;

FIG. 5 is a front elevational view thereof, on an enlarged scale, showing the narrower central wall portion, the rear elevational view being identical; and,

FIG. 6 is a side elevational view thereof, on an enlarged scale, from the view point of one of the legs the view from all the legs, being identical.

FIG. 1

FIG. 2

FIG. 3

FIG. 4

FIG. 5

FIG. 6
